John S. Visscher,
His Attorney.

UNITED STATES PATENT OFFICE

2,176,753

SUPPORT FOR WASHING MACHINES AND
THE LIKEJohn S. Visscher, Stratford, Conn., assignor to
General Electric Company, a corporation of
New York

Application July 7, 1937, Serial No. 152,317

1 Claim. (CL 248—151)

My invention relates to supports for washing machines and the like.

The object of my invention is to provide an improved construction composed of parts capable of being manufactured cheaply and of being easily and quickly assembled.

For a more detailed understanding of my invention reference may be had to the following description and the appended claim.

In the accompanying drawing, Figure 1 shows a domestic washing machine having a supporting structure embodying my invention; Figure 2 is a perspective view of the upper portion of one of the legs; and Figure 3 is a sectional view taken along line 3—3 in Figure 1.

Referring to the drawing, there is shown a domestic washing machine having a cylindrical sheet metal tub 10 supported on a supporting structure comprising a cylindrical sheet metal skirt 11 and legs 12. The upper edge of the skirt 11 has an outwardly flaring rim 13 providing a seat for the tub. A strip 14 of rubber or other non-metallic composition lies between the tub and the rim of the skirt, the upper edge 15 of the strip 14 fitting over the upper edge of the skirt. The lower edge 16 of the strip 14 is bead shaped to conform more closely to the bottom of the tub. The strip 14 provides a seal which prevents leakage between the tub and the skirt of water which may flow down the outside of the tub. The lower edge 30 of the skirt 11 is rolled inwardly and provided with a stiffening bead 17.

The driving mechanism for the washing machine may be supported on the skirt. Suitable arrangements (not shown) are provided for holding the tub against the upper edge of the skirt.

Each of the legs 12 is formed of sheet metal in a channel shape, wide at the central portions and narrow at each end. As is shown clearly in Figure 2, the side walls 18 of the legs have hook-shaped projections 19 formed integrally therewith near the upper end of the leg. These projections 19 extend through slots 20 in the skirt and hook over the inner surface of the skirt, fastening the legs to the skirt. The upper edges of the slots 20 rest on the bottom portions 19a of the hooks, transferring the load from the skirt to the legs.

Near the wide central portion of the legs, the side walls 18 have integral tabs 21 which extend

through slots 22 in the skirt and are subsequently bent outward to hold the legs against the skirt. Shoulders 23 formed in the side walls 18 cooperate with the inwardly curved lower edge of the skirt and provide additional support therefor.

The lower ends of the legs are braced by radial tension arms, connected to each other at the center in a manner not shown and provided with down-turned tabs 25 fastened to the legs by bolts 26. The arms 24 tend to draw the lower ends of the legs inwardly forcing the shoulders 23 against the curved lower edge of the skirt and urging the hooks 19 outward against the inner surface of the skirt. The tension arms 24 increase the stability and strength of the structure by removing any possibility of play between abutting parts of the legs and the skirt. Casters 28 are suitably carried by lower ends of the legs.

In assembly the hooks 19 of the legs are inserted through the slots 20 in the skirts and the legs pushed upward until the bottom portions 19a of the hooks bear against the upper edges of the slots. The legs are then swung toward the skirt, pivoting about the upper edges of the slots 20, and the tabs 21 extended through openings 22 in the skirt. The tabs 21 are then bent outward, locking the legs to the skirt. The tension arms 24 are attached to each other and to the legs drawing the lower ends of the legs inward and forcing the shoulder 23 on the legs tightly against the inwardly curved edge of the skirt. The legs are now held tightly on the skirt. The load carried by the skirt is transmitted to the legs through the upper edges of the slots 20 which bear on the portions 19a of the hooks 19 and through the lower curved edge of the skirt which bears on the shoulders 23.

What I claim as new and desire to secure by Letters Patent of the United States is:

In combination, a skirt having spaced openings 40 therein, a channel-shaped leg having its side walls presented edgewise to and engaging one face of the skirt and having the connecting walls spaced therefrom, integral hook-shaped portions on the edges of and facing along the side walls, said hook-shaped portions being inserted through said openings and cooperating with the opposite face of the skirt to hold the legs thereon, and means for holding the leg against the skirt.

JOHN S. VISSCHER. 50
